UNITED STATES PATENT OFFICE

120,658

DESIGN FOR A COMBINED LIGHT TRANSMITTING PANEL AND GLOBES FOR A LIGHTING FIXTURE

Albert L. Arenberg, Highland Park, Ill., assignor to Patent License Corporation, Chicago, Ill., a corporation of Illinois

Application April 5, 1939, Serial No. 84,049

Term of patent 14 years

To all whom it may concern:

Be it known that I, Albert L. Arenberg, a citizen of the United States, residing at Highland Park, in the county of Lake and State of Illinois, have invented a new, original, and ornamental design for a Combined Light Transmitting Panel and Globes for a Lighting Fixture, of which the following is a specification, reference being had to the accompanying drawing, forming a part thereof.

In the drawing:

Fig. 1 is a perspective view of the combined light transmitting panel and globes for a lighting fixture, showing my new design;

Fig. 2 is a front elevational view of the combined panel and globes for a lighting fixture;

Fig. 3 is a side elevational view of the same; and

Fig. 4 is an end elevational view of the same.

The entire panel is translucent, and the surfaces of the panel which are shown stippled in the drawing are of a character to diffuse the light passing through such surfaces.

I claim:

The ornamental design for a combined light transmitting panel and globes for a lighting fixture, substantially as shown and described.

ALBERT L. ARENBERG.
